CLAIM

The ornamental design for a shopping basket, as shown and described.

DESCRIPTION

FIG. 1 is an isometric view of the shopping basket;

FIG. 2 is a left side elevation view thereof;

FIG. 3 is a right side elevation view thereof;

FIG. 4 is a rear elevation view thereof, the front elevation view being a mirror image thereof;

FIG. 5 is a top view thereof; and,

FIG. 6 is a bottom view thereof.

The heavy, short, broken lines shown in FIGS. 1-6 represent stitching and do form part of the claimed design.

The broken lines are for the purpose of illustrating the environment of the article only and form no part of the claimed design.
